UNITED STATES PATENT OFFICE.

ALEXANDRE MARIE JOSEPH EUGÈNE REBOUL, OF CONSTANTINOPLE, TURKEY.

FOLDING SAFETY-RAZOR.

1,393,700.

Specification of Letters Patent.

Patented Oct. 11, 1921.

Application filed November 3, 1913. Serial No. 798,821.

(GRANTED UNDER THE PROVISIONS OF THE ACT OF MARCH 3, 1921, 41 STAT. L., 1313.)

To all whom it may concern:

Be it known that I, ALEXANDRE MARIE JOSEPH EUGÈNE REBOUL, a citizen of the French Republic, residing at Constantinople, 5 in Turkey, have invented certain new and useful Improvements in Folding Safety-Razors, of which the following is a specification.

The object of the present invention is a folding safety razor of which the characteristic feature consists in the fact that the handle, constituted by two folding arms fitting within one another, is provided with grips which, when the handle is extended, automatically engage the blade and hold it in position for use and when the handle is closed, automatically free the blade. This arrangement allows of instantly freeing the blade in order that one can sharpen it, turn it or replace it by the simple folding of the arms 10 constituting the handle, against the frame, the whole then occupying the minimum of space.

A form of construction of this system of razor is represented by way of example by 25 the annexed drawing in which —

Figure 1 is a perspective view of the razor in position for use.

Fig. 2 is a similar view of the frame with its handle folded, the blade being separated 30 from the frame.

Figs. 3 and 4 are views in plan of the razor corresponding respectively to positions shown in Figs. 1 and 2.

Fig. 5 is a transverse section on the line 35 A—A of Fig. 1.

The razor is composed of a blade carrying plate *a* of which the long side corresponding to the edge of the razor blade can be either oblique or perpendicular to the ends and is 40 provided with a row of directing teeth *b* parallel to these ends.

At each of its ends the plate *a* has hinges *c* and *d* to which are connected arms *e* and *f* of a length practically equal to that of the 45 plate *a* and arranged so as to be able to be folded on one another and toward the back face of the said plate. For this purpose one of the hinges is arranged to project with regard to the other, so that one of the arms can 50 easily lie under the other in the folded position as shown in Figs. 2 and 4.

The arms *e* and *f* are provided with lugs *g* *h* extended beyond their hinges and bent so as to project over the ends of the plate *a* when

the arms *e* and *f* are in the position for use 55 shown in Figs. 1 and 3, so that the said lugs then engage over the ends of the razor blade *l* to maintain it rigidly pressed in position on the plate *a*, as shown in Figs. 1 and 3.

The blade *l* is sharpened along its two longitudinal sides, which may be either oblique or perpendicular to the short sides.

This blade *l* is provided with two holes *o* which are adapted to fit over two corresponding pins *m* arranged on the plate *a*. The 65 holes *o* and the pins *m* are arranged so that the blade *l* can be turned end for end without there being any variation in the respective positions of the sharpened parts of the blade and the row of teeth of the plate *a*. 70

The blade *l*, which is made of steel, is slightly curved along its thickness so as to be able to lie flat and be applied exactly along all its length against the frame when one presses its ends under the lugs *g* and *h* in the 75 open position of the arms *e* and *f* (Fig. 3).

The arms *e* and *f* are themselves curved and their hinges are arranged with regard to their respective lugs *g* *h* so that these arms rest the one against the other near their outer 80 ends in the position of use of the razor. This function is facilitated by the fact that the arms are made of a slightly flexible material and that it is sufficient to make the end of one *f* slide with a slight effort against the interior 85 face of the other *e* in order that the two arms rigidly support one another. The arm *e* is provided with an opening *i* in which engages a tenon *j* formed at the end of the arm *f*, this engagement being effected by separating the 90 two arms with a certain amount of force, against the natural spring of the arms, which presses the one against the other when they are left free.

In the extended position of the arms *e* *f* the 95 blade *l* is maintained rigidly against the plate *a* by the lugs *g* and *h*.

To liberate the blade *l* or close the razor after use it is sufficient to fold the two arms *e* and *f* against the back of the plate *a*. 100

The little space which this razor occupies when it is folded allows of putting it with the greatest facility in the pocket of a garment, purse or razor-case.

What I claim as my invention and desire 105 to secure by Letters Patent of the United States is:—

1. In a folding safety razor, the combina-

tion with a plate of two handle members hinged to said plate and foldable onto and from the rear surface thereof, said members having lugs projecting forwardly of the 5 upper surface of the plate and adapted, when the members are extended from the plate, to engage over a detachable razor blade on the upper surface of the plate.

2. In a folding safety razor, the combination with a plate of two arms constituting handle members hinged to said plate, said arms having lugs projecting forwardly of the surface of the plate and adapted, when the arms are extended from the plate, to 10 engage a detachable razor blade, and means for locking the ends of said arms together in their extended position.

3. In a folding safety razor, the combination with a plate of handle members hinged 20 at opposite ends respectively of said plate, said members having lugs projecting forwardly of the surface of the plate, and adapted, when the arms are extended from the plate, to engage a detachable razor blade, 25 said members being adapted to lie one over the other on the rear surface of the plate or to be extended so as to meet and engage one another at their ends when extended.

4. In a folding safety razor, the combination of a plate one edge of which is toothed,

two arms hinged respectively to said plate at opposite sides thereof and adapted to be folded over one another onto the rear surface of said plate, means for locking the ends of said arms together when in their 35 extended position to form a handle, and forwardly projecting lugs on said arms, adapted, when the arms are extended, to engage over the ends of a removable razor blade and press it downward onto the upper 40 surface of said plate.

5. In a folding safety razor, the combination of a plate, two arms hinged respectively to said plate at opposite sides thereof and adapted to be folded one over the other onto 45 the rear surface of said plate, or to be folded outward and to abut the one against the other near the ends thereof and engage one another by their resiliency, and forwardly projecting lugs on said arms, adapted, when 50 the arms are extended, to engage over the ends of a removable razor blade and press it upon the surface of said plate.

In witness whereof I have signed this specification in the presence of two witnesses. 55

ALEXANDRE MARIE JOSEPH EUGÈNE REBOUL.
